UNITED STATES PATENT OFFICE.

SOMMERFIELD E. MILLER, OF CHICAGO, ILLINOIS.

VANITY CASE.

Application filed February 21, 1922. Serial No. 538,229.

To all whom it may concern:

Be it known that I, SOMMERFIELD E. MILLER, a citizen of the United States, residing at Chicago, in the county of Cook and State of Illinois, have invented certain new and useful Improvements in Vanity Cases, of which the following is a specification.

The primary object of the invention is to provide a vanity case having a mirror with a light so positioned within the vanity case as to reflect the face of the user of the mirror therein in the dark.

A further object of the invention is to provide a lamp within a vanity case, the light from which may be turned off or on at will.

A further object of the invention is to so position the means for operating a light within a vanity case that it can be conveniently operated by the thumb of the hand with which the user holds the case.

Other objects of the invention will appear from the following description, which is directed to the preferred embodiment of the invention, reference being had to the accompanying drawing, and as more clearly set forth in the appended claim.

In the said drawings, Fig. 1 is a perspective view of the invention showing a vanity case with a mirror, an incandescent lamp, a battery, and a switch button within the case,

Fig. 2 is a front view of a fiber plate showing the switch, incandescent lamp and contact members for the battery.

Fig. 3 is a rear view of the fiber plate showing the electric wires with their respective terminals.

Fig. 4 is an end view of the dry battery taken on line 4-4 of Fig. 1, looking in the direction of the arrows, showing the poles of the battery in contact with wire terminals, and showing the fiber plate in cross section.

Fig. 5 is a top plan view of the fiber plate showing the switch in open position.

Fig. 6 is a vertical sectional view taken on line 6-6 of Fig. 2, looking in the direction of the arrows.

For a more particular and comprehensive understanding of the invention reference may be had to the reference characters of the drawings, in which reference character 10 indicates the body portion of the vanity case having hinged

cover 11, in which is placed a mirror 12 as is usual in such devices. Secured to the rear wall 13 of the case 10 and between the wall and the lining 14 of the case is insulating plate 15, which may be made of any suitable insulating material, preferably fiber board. In order to throw the rays of light from the lamp 16 onto the mirror and the face of the person using the mirror the arm 17 supporting the lamp is extended outwardly and upwardly from the rear wall 13. Envelope 18 having flap 19 with snap 20 is secured to the rear wall 13 of the case 10 for removably securing therein dry battery 21. Poles 22, 23 of dry battery 21 are adapted to be received between the spring contact members 24, 25, and 26, 27 respectively. Indicator 28 is placed on the lining 14 of the rear wall 13 of case 10 directly over the spring switch 29 and is for the purpose of indicating or locating the switch, which is beneath and concealed by the lining 14 of the rear wall 13. Switch 29 is made of spring metal and is normally in open position, as clearly shown in Fig. 5. The indicator should preferably be made of a material which will be in contrast with the lining of the wall 13 in order that it may be readily seen by the user when it is desired to operate the switch. Switch 29 may be, however, provided with a button, or the like, projecting through the lining on the wall 13. When switch 29 is pressed into contact with plate 30 the circuit will be closed through the contact formed between the pole 22 contacting members 24 and 25, wire 31, plate 30, switch 29, wire 32 to the lamp 16, thence to contact plate 33 through wire 34 to contact plate 35 to contacting members 26, 27 to pole 23 of the dry battery 21. In order to place the circuit wires on the rear face of fiber plate 15 contact plates 30, 33 and 35 are made in the form of clips adapted to receive the edge of fiber plate 15 therein with one side of the clip lying on the front face of the plate and the other side of the clip lying on the rear side of the plate. It is obvious, however, that the wires may be placed on the front face of the fiber plate and the connections made in any way deemed desirable. It will be noted that switch 29 is placed on the rear wall 13 of the case 10 and adjacent the left hand end thereof. The object and purpose of locating the switch in this position is that the

user of the vanity case may support the case with the left hand with the thumb extended over the left hand end wall of the case in such position as to readily manipulate the switch with the thumb while at the same time the mirror may be controlled by the first and second fingers of the hand supporting the case.

insulating plate intermediate one of the walls and the lining, a lamp, circuit wires and a concealed switch supported by the plate, a battery within the case, contacts between the battery and the circuit wires, a cover hingedly related to the case, and a mirror supported by the cover.

In testimony whereof I have signed my name to this specification, on this 17th day 15
of February, A. D. 1922.

SOMMERFIELD E. MILLER.

- What I claim is:
10 The combination with a case having a lining on the interior walls thereof, of an
